UNITED STATES PATENT OFFICE.

EUGENE T. VINCENT, OF BOSTON, MASSACHUSETTS.

DESIGN FOR A THERMOSTAT MOUNTING.

Application filed June 16, 1928. Serial No. 27,168. Term of patent 7 years.

To all whom it may concern:

Be it known that I, EUGENE T. VINCENT, a citizen of the United States, and a resident of Boston, in the county of Suffolk and State of Massachusetts, have invented a new, original, and ornamental Design for Thermostat Mountings, of which the following is a specification, reference being had to the accom-

panying drawing, forming part hereof, and in which the figure is a perspective view of the article, showing my new design.

I claim:

The ornamental design for a thermostat mounting, as shown.

EUGENE T. VINCENT.
